(57) **CLAIM**

The ornamental design for a micro speaker, as shown and described.

DESCRIPTION

FIG. 1 is a top perspective view of a micro speaker.
FIG. 2 is a front view of a micro speaker.

FIG. 3 is a rear view of a micro speaker.

FIG. 4 is a left side view of a micro speaker.

FIG. 5 is a right side view of a micro speaker.

FIG. 6 is a top view of a micro speaker; and,

FIG. 7 is a bottom view of a micro speaker.

The broken lines shown in the drawings represent unclaimed portions of the micro speaker and form no part of the claimed design.
